UNITED STATES PATENT OFFICE.

HARPER F. SMITH, OF PHILADELPHIA, PENNSYLVANIA.

VAPOR-LAMP GOVERNOR.

SPECIFICATION forming part of Letters Patent No. 759,036, dated May 3, 1904.

Application filed June 27, 1903. Serial No. 163,303. (No model.)

To all whom it may concern:

Be it known that I, HARPER F. SMITH, a citizen of the United States, residing at Philadelphia, in the county of Philadelphia and State 5 of Pennsylvania, have invented a new and useful Improvement in Vapor-Lamp Governors, of which the following is a specification.

My invention relates to a governor adapted to control the flow of liquid and vaporized hydrocarbon or like volatile fluid in a lamp or 10 heating device.

It consists of a governor exterior to the reservoir, through which passes all the hydrocarbon used both in its liquid and in its vaporized form.

It also consists of a unitary device for controlling the flow through a governor of both such liquid and such vapor.

It also consists of means for connecting the 20 governor, the reservoir, and the vaporizing portions of the lamp or heater.

It further consists of other novel features of construction, all as will be hereinafter fully set forth.

25 In a former application, filed by me April 30, 1903, Serial No. 154,970, I have shown and described a novel vapor-lamp having a governor and feed-regulating device partially inclosed in a reservoir. In a division of that 30 case, application Serial No. 162,310, I have shown, described, and claimed such governor.

In the present application I have shown the governor exterior to the reservoir, although some features of my invention need not be 35 limited to this construction.

Figure 1 represents a partial elevation and partial vertical section of a vapor-lamp embodying my invention. Fig. 2 represents a similar view of the governing device and its 40 connections on an enlarged scale. Fig. 3 represents in vertical section a detail of a connection.

Similar numerals of reference indicate corresponding parts in the figures.

45 Referring to the drawings, 1 designates a reservoir of a vapor-lamp. 2 designates a vaporizer or generator in which, after the lamp is in operation, the liquid hydrocarbon or fuel, hereinafter designated as "oil," is vaporized.

50 3 designates a superheater or regenerator in

which such vapor is superheated and from which it is discharged through the outlet-ori- 55 fice 4 into a commingling-tube 5, leading to the burners 6. 7 designates a starting de- vice wherein a temporary flame may be gen- 60 erated to heat the parts 2 and 3. As all these parts are shown and fully described in my application above named and as they form *per se* no part of my present invention, I will not here refer to them except as it is neces- 65 sary to describe the form and operation of the devices hereby sought to be protected.

Suitably supported at a convenient distance from the reservoir 1 is a governor-casing 8, into which is a fluid-inlet 9, connected by a 65 tube 10 with the reservoir 1 and opening into an inlet-chamber 11, beneath which is an out- let-chamber 12, having a fluid-outlet 13, con- 70 nected by a tube 14 to the generator 2 and by a second tube 15, in which is a cock 16, to the 75 starter 7. Within the chamber 11 and extend- ing substantially above the inlet 9 is a strainer, 80 shown as a perforate or reticulate tube 17, surrounded by a sleeve 18, which may be of any desired fabric. Between the chambers 11 and 12 is a valve-seat 19, against which rests a valve 20, having an upwardly-extending tu- 85 bular stem 21 and a downwardly-extending portion 22, serving as a guide for a thrust- 90 spring 23, which bears against the valve 20. 80

From the upper tube of the generator 2 rises a tube 24, in which is a cock or valve 25, to a dome 26 on the reservoir 1, from which a tube 27 leads to a vapor-inlet 28, communicating with a vapor-chamber 29 in the casing 8. A 85 second tube 30, provided with a cock 31, also connects the generator 2 with the chamber 29.

I have shown in Fig. 3 of the drawings a preferred mode of securing in place the ends of the tubes 24 and 30. It consists of an en- 90 larged head 32 at each end of the tube, over which engages a threaded collar 33, by which it may be connected to the nipple. In Fig. 2 I have shown the tube 30 removed and the inlet-nipple 34 closed by a "blind eye" or 95 stud 35, having a solid head and held in place by a collar 33, similar to that shown in Fig. 3.

From the vapor-chamber 29 rises a tubular portion forming a passage 36, above which is a diaphragm-box 37, the upper end of which 100

is closed by a cap 38. A rod 39 moves freely in the passage 36 and, as shown, passes through a diaphragm-chamber 40, to the upper shell of which it is tightly secured. To the lower shell of the chamber 40 is secured a collar 41, so that the diaphragm-chamber communicates with the passage 36. A thrust-spring 42 extends between the diaphragm-casing 40 and the cap 38. Attached to the lower end of the rod 39 is a fitting 43, from which depends a second rod 44, the lower threaded end of which slides smoothly on the tubular stem 21 of the valve 20. Lock-nuts 45 are placed on the rod 44, the function of which will hereinafter appear. Pivotal or otherwise attached to the fitting 43 is the stem 46 of a valve 47, which controls the port to the regenerator 3.

The operation is as follows: By momentarily opening cock 16 in tube 15 a small amount of oil is introduced into the starter 7, the valve 20 being normally open. The heat produced by the combustion of this oil vaporizes that contained in the generator 2, the vapor flowing to the vapor-chamber 29 in the governor 8 either through the tube 24, dome 26, and tube 27 or directly through the tube 30 to the vapor-chamber 29 of the governor 8. I have provided these two means of communication between the generator and the vapor-chamber to insure a free flow of vapor at all times. If one of the tubes 24 or 30 should become obstructed, it may be removed, as for cleaning, and the nipple-aperture closed, as above described. I have shown that either or both of these tubes may be provided with cocks or shut-off valves, if desired. The closing of one of these, thus forcing the entire flow through the other tube, will often suffice to clear it. The vapor flowing through either or both of these chambers into the chamber 29 normally flows out through the tube 48 to the regenerator 3, where it is highly superheated and where it is forced through the orifice 4. The rushing vapor acts to draw in air into the commingling-tube 5, the mixed air and vapor passing to and being consumed in the burners 6. As the diaphragm-chamber 40 communicates, through the passage 36, with the chambers 11 and 29 of the governor, any excess above a predetermined pressure therein will expand the diaphragm and raise the rod 39, fitting 43, rod 44, and valve-stem 46. This permits the spring 23 to close the oil-controlling valve 20, whereby the supply to the generator 2 is temporarily cut off. Any further excess of pressure beyond the point of cutting off the flow of oil will cause further expansion of the diaphragm-chamber 40 and force valve 47 to its seat. This shuts off the flow of vapor to regenerator 3 and extinguishes flame. By adjusting the lock-nuts 45 on the rod 44 the relative motion of the valves 47 and 20 may be accurately determined, while the action of the double device is controllable by

varying pressure on the compression-spring 42 through the cap 38. It is evident that a reduction of pressure in the governor 8 through combustion of the vapor at the burners 6 will permit the spring 42 to reopen the oil-inlet 70 valve 20 and the vapor-outlet valve 47 to the desired extent.

It will be seen that the governing device provides a simple, efficient, and unitary means of controlling the entire flow of both oil and vapor, both of which necessarily pass therethrough. The oil entering at 9 passes through a strainer 17 18, thence past the valve 20 to the outlet 13. The vapor from the generator 2 may either pass upward to the reservoir, 80 thence to the vapor-chamber in the governor, or, conversely, it may pass first to the governor, thence to the reservoir. In any case it can only reach the point of combustion by first passing the valve 47, which acts as a 85 safety-valve to modify or entirely cut off the flow when the pressure rises above a predetermined point.

By placing the governor entirely independent and exterior of the reservoir any defect of 90 construction or possible leak may be detected and amended.

By constructing the governor, as clearly shown in Fig. 2, with threaded closures at each end and threaded connections between 95 the chamber 11 and the parts above and below it the whole device may be readily taken apart for cleaning or repairs.

It will be evident that various changes may be made by those skilled in the art which will 100 come within the scope of my invention, and I do not, therefore, desire to be limited in every instance to the exact construction herein shown and described.

Having thus described my invention, what 105 I claim as new, and desire to secure by Letters Patent, is —

1. In a vapor-burning device, a reservoir, a vaporizer, a burner, connections from said reservoir to said generator and from said generator to said burner and a unitary set of means actuated by the pressure of the generated vapor for controlling the flow of fuel to the vaporizer and of vapor to the burner. 110

2. In a vapor-burning device, a reservoir, a 115 vaporizer, a burner and a governor interposed between said reservoir and said vaporizer and between said vaporizer and said burner, said governor comprising means for controlling the flow of both oil and vapor. 120

3. In a vapor-burning device, a reservoir, a vaporizer, a burner and a governor interposed between said reservoir and said vaporizer and between said vaporizer and said burner and forming a necessary part of the means of communication between said reservoir and said vaporizer and between said vaporizer and said burner, said governor comprising means for controlling the flow of both oil and vapor. 125

4. In a vapor-burning device, a reservoir, a 130

vaporizer, a burner and a governor interposed between said reservoir and said vaporizer and between said vaporizer and said burner, said governor comprising means for controlling the flow of both oil and vapor and having oil and vapor chambers in fluid connection with each other.

5. In a vapor-burning device, a reservoir, a vaporizer, a burner, a governor interposed between said reservoir and said vaporizer and between said vaporizer and said burner and successively-operated valves in said governor for controlling the flow of the oil and the vapor.

6. In a vapor-burning device, a reservoir, a vaporizer, a burner, a governor interposed between said reservoir and said vaporizer and between said vaporizer and said burner, separate valves in said governor for controlling the flow of oil and of vapor and a diaphragm actuated by vapor-pressure and operatively connected with both said valves.

7. In a vapor-burning device, a reservoir, a vaporizer, a burner, a governor interposed between said reservoir and said vaporizer and between said vaporizer and said burner, separately-adjustable valves in said governor for controlling the flow of oil and of vapor and a diaphragm actuated by vapor-pressure and operatively connected with both said valves.

8. In a vapor-burning device, a reservoir, a vaporizer, a burner, a governor controlling the flow of fluid from said reservoir to said burner and separate means whereby vapor is conducted from said vaporizer, one leading through said governor to said reservoir and the other leading through said reservoir to said governor.

9. In a vapor-burning device, a reservoir, a vaporizer, a burner, a vapor-actuated governor controlling the flow of fluid from said reservoir to said burner, means providing separate passages for conducting vapor from said vaporizer, one leading through said governor to said reservoir and the other leading through said reservoir to said governor and means for closing said passages.

10. In a vapor-burning device, a reservoir, a vaporizer, a burner, a vapor-actuated governor controlling the flow of fluid from said reservoir to said burner, a tube leading from said vaporizer to said reservoir, a second tube leading from said vaporizer to said governor and a tube between said reservoir and said governor.

11. In a vapor-burning device, a reservoir, a vaporizer, a burner, a vapor-actuated governor controlling the flow of fluid from said reservoir to said burner, a removable tube leading from said vaporizer to said reservoir, a second removable tube leading from said vaporizer to said governor and a tube between said reservoir and said governor.

12. In a vapor-burning device, a reservoir, a vaporizer, a burner, a unitary set of means exterior of said reservoir and adapted to con-

trol the flow of oil from said reservoir to said vaporizer and the flow of vapor from said vaporizer to said burner, said controlling means being operative when the pressure of the generated vapor exceeds a predetermined limit.

13. In a vapor-burning device, a reservoir, a burner, a governor controlling the flow of fluid from said reservoir to said burner, a vaporizer, means whereby oil is conducted from said reservoir to said governor and from said governor to said vaporizer, means providing a plurality of vapor-passages from said vaporizer to said governor and said reservoir and a vapor-passage from said governor to said burner.

14. In a vapor-burning device, a reservoir, a burner, a governor controlling the flow of fluid from said reservoir to said burner, a vaporizer, a superheater, means providing an oil-passage from said reservoir to said governor and from said governor to said vaporizer, means providing a plurality of vapor-passages from said vaporizer to said governor and said reservoir and means providing a vapor-passage from said governor to said superheater.

15. In a vapor-burning device, a governor comprising separate oil and vapor controlling valves and means operative to positively move one of said valves in both directions and the other of said valves in one direction.

16. In a vapor-burning device, a governor comprising separate oil and vapor controlling valves and pressure-controlled means operative to positively move one of said valves in both directions and the other of said valves in one direction.

17. In a vapor-burning device, a vapor-actuated governor comprising separate oil and vapor controlling valves, a diaphragm operative to positively move one of said valves in both directions and the other of said valves in one direction and means for regulating the movement of said diaphragm.

18. In a vapor-burning device, a reservoir, a burner, a vapor-actuated governor controlling the flow of fluid from said reservoir to said burner, a vaporizer, a tube connecting the upper portions of said reservoir and said governor and vapor-conducting tubes leading from said vaporizer, one to said governor, the other to said reservoir.

19. In a vapor-burning device, a governor adapted to control the flow of both oil and vapor passing therethrough and comprising a valve for checking the flow of oil, a valve for checking the flow of vapor and vapor-actuated means for positively moving said last-named valve to open and close the same and for moving said first-named valve to open the same.

20. In a vapor-burning device, a governor adapted to control the flow of both oil and vapor passing therethrough and comprising a spring-actuated valve for checking the flow of oil, a valve for checking the flow of vapor and a diaphragm operative to close said vapor-

checking valve and to release said spring-actuated valve.

21. In a vapor-burning device, a reservoir, a vaporizer and a governor controlled by fluid-pressure generated in said vaporizer and operative by an increase of such pressure to cut off the flow of hydrocarbon to said vaporizer and by a further increase of such pressure to extinguish the flame.

22. In a vapor-burning device, a reservoir, a vaporizer and a governor controlled by fluid-pressure and operative by an increase of such pressure to cut off the flow of liquid hydrocarbon to said vaporizer and by a further increase of such pressure to reduce the flow of vaporized hydrocarbon to the burner.

23. In a vapor-burning device, a reservoir, a burner, a vaporizer located in the heat zone of said burner, a governor interposed between said vaporizer and said burner and automatically operated by the pressure generated in said vaporizer to control the flow of vapor to said burner, and means located in the heat zone of said burner interposed between said governor and said burner for superheating such vapor.

24. In a vapor-burning device, a reservoir,

a burner, a vaporizer located in the heat zone of said burner, a governor interposed between said vaporizer and said burner, comprising a valve controlling the flow of vapor to said burner and a diaphragm actuated by pressure of vapor generated in said vaporizer and operative to close such valve thereby extinguishing the flame, and means located in the heat zone of said burner and interposed between said governor and said burner for superheating such vapor.

25. In a vapor-burning device, a reservoir, a governor, a vaporizer and a superheater, pipes leading from said reservoir to said governor, thence to said vaporizer, thence to said governor and thence to said superheater, a valve in said governor controlling the flow of hydrocarbon from said reservoir to said vaporizer and a second valve controlling the flow from said vaporizer to said superheater, and pressure-operated means in said governor for closing said valves in the order named.

HARPER F. SMITH.
